Primary Examiner — Patricia A Palasik

(57) **CLAIM**

The ornamental design for a vacuum fixture plate, as shown and described.

DESCRIPTION

FIG. 1 is a perspective view showing the vacuum fixture plate embodying the new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof, the right side elevational view being a mirror image thereof; and,

FIG. 7 is an enlarged detail perspective view taken from lines 6-6 of FIG. 1.

The broken lines in the drawing views depict environment that forms no part of the claimed design. The dot dash broken lines illustrate a boundary that forms no part of the claimed design.

1 Claim, 6 Drawing Sheets
